PATRICK W. SHIELDS, OF PITTSBURGH, AND LOUIS DE MARKUS, OF MONTROSE, PENNSYLVANIA, ASSIGNORS TO MCKENNA BRASS & MANUFACTURING COMPANY, INC., OF PITTSBURGH, PENNSYLVANIA, A CORPORATION OF PENNSYLVANIA.

CARBONATOR.

Application filed September 29, 1922. Serial No. 591,288.

The present invention relates broadly to bottling soft drinks which require a comparatively low carbonation, and to a method of effecting the desired carbonation.

5 In the soft drink industry it is common practice to carbonate or charge ordinary water with from 2 to 8 times its own volume of carbon dioxide, the degree of carbonation depending on the product desired. In ordinary carbonators there is usually provided an excess of carbon dioxide to insure carbonation up to the saturation point of the water at carbonator temperature and pressure. As with certain drinks, such for 10 example as imitation grape drinks, it is desirable to provide only sufficient carbon dioxide to impart the desired palatable characteristics to the drink, it will be apparent that a carbonator which effects carbonation up to substantially the saturation point 15 would not be suitable for directly supplying its water to a bottling machine bottling drinks of this character.

By the present invention there is provided improved means for supplying carbonated water of the proper characteristics to bottling machines, it being understood that the term "bottling" as used herein is definitive both of bottle filling and 20 bottle filling and capping machines.

In the accompanying drawings, there is shown for purposes of illustration only a certain embodiment of the present invention, these drawings being largely diagrammatic 25 and representing apparatus which may be of any desired construction and in which changes may be made in the construction and operation without departing from the spirit or scope of our broader claims.

40 In the drawings:

Figure 1 is a chart in rectangular coordinates showing the relation between temperature, pressure, and saturation point of carbon dioxide in water, and

45 Figure 2 is a diagrammatic view illustrating one embodiment of this invention.

Experience in the use of bottling machines has demonstrated the advisability of supplying thereto, where carbonated water is required, carbonated water at comparatively definite pressures. These pressures

vary with different machines in accordance with the design thereof, but each particular machine operates efficiently only over a comparatively definite pressure range. By 55 the present invention it is possible not only to effect the desired carbonation, but to supply the carbonated water at the pressure required by the bottling machine.

Referring first to the chart of Figure 1, 60 the horizontally extending dotted line represents the pressure at which the bottling machine, not shown in the drawings, is best adapted to operate. The lowest and highest temperatures at which tap water is found 65 during the year, are represented respectively by the reference characters t' and t'' . During the cold months the water temperature will be close to t' , while it will approach t'' during the hotter months. An average condition is arbitrarily represented by t . The intersection of a line drawn from t with the dotted line representing bottling machine pressure will show that under these conditions the saturation point of the water is 70 at about $4\frac{1}{3}$ volumes. As has been before referred to, a carbonator which is commercially efficient will produce a substantially saturated solution at its temperature and pressure, the pressure and temperature being 75 determined respectively by the pressure of the bottling machine and the temperature of the tap water.

This degree of carbonation, viz: substantial saturation, is not suitable, for the 80 reasons pointed out, for use in bottling certain soft drinks requiring low carbonation. It is extremely difficult, if not impossible, with known apparatus to effect uniform carbonation at under-saturation in ordinary 85 carbonators. This has been due to the difficulty encountered in maintaining the desired proportions of water and carbon dioxide. By this invention the carbonator is operated in its normal way to produce substantial 90 saturation and then this substantially saturated water is treated to render it capable of absorbing additional carbon dioxide. This result may be accomplished in different ways, either by increasing the 95 pressure after carbonation as disclosed in our co-pending application Serial No. 591,

289, filed September 29, 1922, or by diluting the substantially saturated water with any desired amount of sweet or uncarbonated water as specifically disclosed hereinafter.

5 Referring more particularly to Figure 2 of the drawings, there is illustrated diagrammatically a carbonator 2 which is adapted to carbonate substantially to saturation, as is customarily done. This carbonator may be 10 provided with any desired connection 3 for supplying the carbon dioxide thereto. The water to be carbonated may be supplied under a definite pressure, preferably corresponding to the bottling machine pressure, 15 by a suitable pump 4 having an inlet 5 and an outlet 6 operatively connected to the carbonator. The carbonated water may leave the carbonator through a suitable connection 7 leading to a mixing chamber 8 of any desired 20 construction. In this chamber the water is treated, by the addition of sweet water thereto, whereby an under-saturated solution, containing a definite percentage of carbon dioxide with respect to the total volume of water, 25 is produced.

We have found that this result may advantageously be produced by providing a bypass 9 leading from the outlet 6 of the pump to the mixing chamber. This bypass is preferably constructed to have the flow there-through automatically proportioned to the flow of water from the carbonator in order to effect the desired definite carbonation. This may be accomplished by providing in 35 the bypass 9 a suitable valve 10 which is operatively connected to a diaphragm 11. This diaphragm may be mounted in a casing 12 of any usual construction, and is subjected on one side thereof to the pressure of the 40 carbonated water in the pipe 7 by a suitable passage 13, and on its opposite side, by a passage 14, is subjected to the pressure of the sweet water just prior to its entrance into the mixing chamber. In order to insure the 45 proper proportioning between the carbonated and the sweet water, the carbonated water preferably enters the mixing chamber through a calibrated orifice 15. The sweet water likewise may be supplied to the mixing 50 chamber 8 through a similar orifice 16. The orifice 16, however, is provided with a regulating valve 17 by means of which the extent of opening of this orifice may be regulated. It will be apparent that this construction 55 produces a differential pressure on opposite sides of the diaphragm 11, which pressure is in turn effective for automatically controlling the position of the valve 10 and thereby maintaining the desired proportions.

60 To insure proper intermingling of the sweet and carbonated waters, the mixing chamber may be provided with agitating means such as baffles 18. From the mixing chamber the water, which is now under-saturated, 65 may pass to the bottling machine

(not shown) through a suitable connection 19.

It will be apparent to those skilled in the art that the pump 4 may be operated at a speed which will insure the supply of a total 70 amount of water through the mixing chamber which is just sufficient to meet the demands of the bottling machine. In this manner, it is possible to obviate the use of objectionable storage tanks, and the like. 75 This construction provides a continuously running carbonating apparatus of simple construction.

If desired, there may be provided a supplemental valve 20 adapted to completely 80 close the calibrated orifice 15. With such a construction, by closing the valve 20 the apparatus may be used for the bottling of still goods requiring no carbonation. When operating in this manner, the water will be 85 supplied through the line 5 at a pressure lower than the bottling machine pressure, the pressure will be raised by the pump 4 to the desired bottling machine pressure and this water will then be fed to the bottling 90 machine. At such times, it will be obvious that the carbonator 2 functions merely as a leading chamber automatically maintaining the desired bottling pressure for the sweet 95 water.

The advantages of the present invention arise from the provision of a carbonating apparatus and method of carbonating for use in connection with bottling machines by means of which uniformly carbonated water 100 at under-saturation may be expeditiously produced.

Further advantages of this invention arise from the provision of a continuously running carbonator which does not require storage tanks and the usual appurtenances 105 thereof.

We claim:

1. In a carbonating apparatus, a water pump having a divided discharge, a carbonator communicating with one division of said discharge, a mixing chamber communicating with the other division of said discharge, a connection between said carbonator and said mixing chamber, and a discharge connection from said mixing chamber, substantially as described.

2. In a carbonating apparatus, a water pump having a divided discharge, a carbonator communicating with one of the divisions 120 of said discharge, a regulator communicating with another division of said discharge, a mixing chamber operatively connected to both the carbonator and said regulator, and a discharge connection from said mixing 125 chamber, substantially as described.

3. In a carbonating apparatus, a mixing chamber, a pump, a plurality of water supply lines between said pump and said mixing chamber, and means in one of said supply 130

lines for carbonating the water flowing therethrough, substantially as described.

4. In a carbonating apparatus, a mixing chamber, a continuously operating pump having a divided discharge supplying water to the mixing chamber, and means in one portion of the discharge for carbonating the

water flowing therethrough to substantially the saturation point, substantially as described.

In testimony whereof we have hereunto set our hands.

PATRICK W. SHIELDS.
LOUIS DE MARKUS.
